United States Patent Office

Des. 196,801
Patented Nov. 5, 1963

196,801

GAME TOP

Stanton L. Friedman, 4719 La Branch, Dallas, Tex.

Filed Mar. 21, 1962, Ser. No. 69,364

Term of patent 14 years

(Cl. D34—15)

FIG. 1 is a plan view of a game top showing my new design;

FIG. 2 is a side view thereof; and

FIG. 3 is a bottom view thereof.

I claim:

The ornamental design for a game top, as shown.
